UNITED STATES PATENT OFFICE.

ADOLPHE C. PETERSON, OF MINNEAPOLIS, MINNESOTA.

FLEXIBLE INTERNAL-COMBUSTION MOTOR.

1,200,519.

Specification of Letters Patent.

Patented Oct. 10, 1916.

Application filed January 23, 1912. Serial No. 672,976.

To all whom it may concern:

Be it known that I, ADOLPHE C. PETERSON, a citizen of the United States, residing at Minneapolis, in the county of Hennepin and State of Minnesota, have invented new and useful Improvements in Flexible Internal-Combustion Motors, of which the following is a specification.

My invention relates to internal combustion motors and particularly to such internal combustion motors as are used for such purposes as require a varying application of the power at varying speeds and torques, such as vehicles for locomotion, my motor being so peculiarly adaptable for such purposes, that I style it a flexible internal combustion motor.

The principal objects of my invention are, first, to provide a motor which shall be adapted to the application of power without the use of friction clutches and variable speed gears and similar mechanisms; second, to provide an internal combustion motor which in the application of power, even at varying speeds and torques and in starting shall act without shock and racking of the driven elements; third, to provide an internal combustion motor which may be easily controlled in the application of the power at varying speeds and torques; fourth, to provide an internal combustion motor, which is easily and absolutely reversible at the will of the operator; fifth, to provide an internal combustion motor which shall have large overload capacity; sixth, to provide an internal combustion motor which may, at the will of the operator, operate the driven element even on large overloads at a snail's pace or at high speed; seventh, to provide an internal combustion motor which may be started automatically at the will of the operator; eighth, to provide an internal combustion motor which shall be adapted to the use of low grades of liquid fuel in combination with the above advantages; ninth, to provide an internal combustion motor which shall be a complete working unit with the above advantages and which at the same time shall be simple and economical of construction.

This application presents various improvements in the application of the general principles and devices shown in my Patent Number 1,079,578, issued November 25, 1913.

Generally stated, my invention consists of the novel devices and combinations of de-

vices hereinafter described and defined in the accompanying claims.

In the accompanying drawings which illustrate my invention like characters refer to like parts throughout the several views.

Referring to the drawings: Figure 1, is a view partly in elevation and partly in vertical section on the line x^1-x^1 of Fig. 2, some parts being shown in diagram only. Fig. 2, is a plan view of the motor shown in Fig. 1. Fig. 3, is a detail plan view of the shifting yoke 85. Fig. 4, is a diagram illustrating the periodic air pressure delivery into the engine cylinders 2 and 3 under so-called forward motion of the motor. Fig. 5, is a diagram illustrating the periodic air pressure delivery into the engine cylinders 2 and 3 under so-called reverse motion of the motor. Fig. 6, is a diagram illustrating operation of one of the air-distributing systems and the oil distributing system in unison or under extreme load. Fig. 7, is a diagram illustrating operation of the fuel distributing system alone.

The numeral 1 indicates the engine crank case and the numerals 2 and 3 the engine cylinders, of an internal combustion engine. An engine crank shaft 4 rotatably mounted in bearings in the crank case 1 has pistons 85 and crank rods coöperating with it and the cylinders 2 and 3.

The crank shaft 4 has constructed integrally with it a flange 5 to which is rigidly secured a compressor unit 6. The compressor unit 6 has two oppositely disposed compressor cylinders 7 formed within it, and has, opposite to the flange 5, integrally constructed with the compressor unit, a bearing 8 which has rotatably mounted within it so as to be concentric with the crank shaft 4, a driven shaft 9. The driven shaft 9 bears with it, eccentrically disposed with respect to its axial center, a crank pin 10. Compressor pistons 11, coöperating with the cylinders 7 and connected with the crank pin 10 by crank rods 12, are reciprocated by rotation of the driven shaft 9 with respect to the compressor unit 6. The compressor cylinders 7 have suction valves 13 which normally close ports in the compressor cylinder heads 14, through which air is drawn into the compressor cylinders 7. Check valves 15 normally retained against ports 16 by springs 17 permit air to be delivered under pressure from the compressor cylinders 7, through conduits 18, to the conduit 19 which

is bored through the engine crank shaft 4, terminating finally in the tube like extension 20 of the engine crank shaft 4, and delivering into the air-dome 21. The air-dome 21 has a stuffing box 22 in which the tube like extension 20 may rotate, and under normal operation of the motor delivers air under pressure into the air-dome 21. The air-dome 21 has a port 23, through which air 10 may be released to the atmosphere, when the so-called clutch valve 24 is lifted from its seat by manipulation of the lever 25. A conduit 26 delivers from the air-dome 21 into an air reservoir 27, a check valve 28 preventing any return flow from the conduit 26 and reservoir 27 to the air-dome 21. A conduit 29 delivers from the reservoir 27 into three branch conduits 30, 31, and 32 which respectively deliver into a spraying 20 chamber 33, and air-distributing chambers 34 and 35, in the distributor 36. Throttle valves 37, 38, and 39 independently control the delivery respectively through each of the conduits 30, 31, and 32, into the spraying 25 chamber and the air-distributing chambers. The distributor 36 has interior partition walls 40, and 41 which isolate the air distributing chambers 34 and 35 from each other and from a third gas-distributing 30 chamber 42 into which the spraying chamber 33 delivers through a port 43. The air-distributing chamber 34 has a port 44 which permits delivery through a conduit 45 and check valve 46 into the cylinder 2, 35 and has also diametrically opposite it a port 47 which permits delivery through the conduit 48, and by the check valve 49 into the cylinder 3. The ports 44 and 47 are uniformly closed and uncovered periodically according to the revolution of the engine crank 40 shaft by a cylindrical valve 50 which is rotated at the same rate of speed as the engine crank shaft 4, by the shaft 51 which is trunnioned in the partition walls 40 and 41 and 45 the lower face 52 of the distributor 36, so that it may be revolved by its attached gear-wheel 53 and the gear-wheel 54 which is secured upon the engine crank shaft 4 so as to rotate with it. The valve 50 has a port 55 50 which is of a length approximating a 120 degree arc of the valve circumference and thereby in its rotation alternately uncovers each of the ports 44 and 47 during about 120 degrees of the revolution of the engine crank shaft 4, this uncovering of each of the ports 55 44 and 47, respectively, being timed to occur during the early part of the working stroke of each engine piston as hereinafter described. The air-distributing chamber 35 60 has similarly ports 56 and 57, which respectively deliver through conduits 58 and 59 and check valves 60, 61 into the engine cylinders 2 and 3, this delivery from the air distributing chamber 35 being controlled by 65 a cylindrical valve 62 which is rotated by the shaft 51 uniformly with the valve 50. This valve 62 has a 120 degree port 63, which is placed so as to be revolved approximately 125 degrees in advance or behind the port 55 in the valve 50, respectively, in motion 70 of the engine-crank shaft 4 in one direction or the other. The port 63 will thereby permit delivery, when properly timed as hereinafter explained, from the chamber 35 through the conduits 58 and 59 into the cylinders 2 and 3, respectively, so as to effect motion in the opposite or so-called reverse motion of the engine crank shaft 4.

The shaft 51 has secured to it, so as to be revolved with it an eccentric 64, whereby a double acting oil pump 65 is actuated through the eccentric rod 66. The oil pump 65 draws oil from the oil tank 67 through the conduit 68 and forces it under a pressure of several hundred pounds through the 85 conduit 69 to the atomizer 70, which sprays the oil into the spraying chamber 33. A conduit 71 permits by-passing the oil from the pump 65 back to the oil tank 67, according to the degree to which the oil valve 72 is 90 opened.

The gas distributing chamber 42 has ports 73 and 74 which communicate through independent conduits 75 and 76 and by non-return valves 77 and 78 with the cylinders 2 95 and 3 respectively. The ports 73 and 74 are controlled by a cylindrical valve 79 which is rotated uniformly with the shaft 51 and has a port 80, approximately as long as a 10 degree arc of the circumference of the valve. 100 This port 80 cooperates with the ports 73 and 74 alternately according to the engine piston movement, under rotation of the shaft 51.

The shaft 51 has loosely fitted upon it so 105 that the shaft 51 may revolve within it, an eccentric 81. This eccentric 81 has constructed integrally with it collars 82 and 83 and a friction disk 84. A shifting yoke 85 coacts with the collars 82 and 83, between 110 them, and is moved upward and downward together with a governor piston 86 to which it is attached. This governor piston 86 slides within the cylinder 87, formed in the upper part of the air-dome 21. A spring 88 acting between the bearing-bracket 89 and the upper face of the eccentric 81, normally presses the eccentric 81 downward so that its attached friction disk 84 engages the disk 90 which is secured to the shaft 51 so as to 115 rotate with it. The eccentric 81, through the eccentric rod 91, under rotation of the shaft 51, actuates the auxiliary pump 91, which, taking air from the atmosphere delivers it at high pressure through the conduit 93 to 120 the air reservoir 27.

The engine cylinders 2 and 3 have each related air passages 94 and 95 through which, by means of the inlet ports 96 and 97, independent communication is had with 125

the independent crank chambers formed in the crank case 1 on each side of the central partition wall 98. The independent crank chambers receive air from the atmosphere by 5 suction valves 99 and 100, and they independently deliver air under pressure through the passages 94 and 95 when the ports 96 and 97 are respectively opened by the pistons 101 and 102 in their reciprocation 10 within the engine cylinders 2 and 3. Exhaust ports 103 and 104, in the engine cylinder walls, also controlled by the pistons 101 and 102 deliver into an exhaust pipe 105, the engine cylinders 2 and 3 being thereby 15 adapted to independently receive a charge of air and discharge the products of combustion as in the usual 2 cycle engine action. Deflectors 106 and 107 are as commonly placed upon the piston heads to deflect the 20 entering charge upward. Spark plugs (not shown) or other ignition means are provided as ordinarily in internal combustion engines.

Operation: In the operation of my flexible internal combustion motor, the engine cylinders 2 and 3 normally each operate in the manner of the common 2 cycle internal combustion engine of the injected fuel type, each of the cylinders 2 and 3 receiving a 25 fresh charge of air from its related crank chamber, after its related piston 102 or 101 has compressed a charge of air into its crank chamber and has uncovered its related port 96 or 97 in its downward reciprocation. 30 Each piston 101 or 102 periodically draws air from the atmosphere into its related crank chamber, and in its downward reciprocation compresses it to such an extent that when its related inlet port 96 or 97 is uncovered, it rushes into the cylinder and is deflected upward by the deflector on the piston head, the burnt gases being thereby expelled as ordinarily in two cycle engines into the exhaust pipe 105. In the normal 35 operation of the motor, each engine cylinder 2 or 3 receives a charge of fuel which is injected into the charge of air at some time before the charge of air has received its maximum compression and slightly before 40 the engine piston has reached its upward limit of stroke. (The injection as the motor is shown will always occur at dead center, so as to be suitable for action of the engine in either direction, but some method 45 of advancing the injection of the fuel with respect to this dead center should preferably be provided.) The charges of air and fuel thus received into the engine cylinders 2 and 50 3 are ignited by the spark plugs 106 or 107 55 or in any manner and the explosion of the air and fuel then produces the effective downward or working stroke of its related piston. The injection of the charges of fuel 60 periodically into the charges of air compressed into the engine cylinders is effected 65

as follows, this being explained in conjunction with an explanation of the means whereby the engine or motor is effectively gotten under way and whereby the motor is adapted to operate under overload: The 70 engine crank shaft 4 is given an initial rotation or is put in operation by opening either the throttle valve 38 or the throttle valve 39, whereby air under pressure is released from the air tank 27 and passes into 75 the engine cylinders 2 and 3 where it acts upon the engine pistons 101 and 102 to put them in motion. The air from the tank 27 is timed to enter the cylinders 2 and 3 so as to produce either forward or reverse motion of the engine crank shaft 4, depending on which of the throttle valves 38 or 39 is opened. When the throttle valve 38 is opened the air passes to the distributor 36 and is permitted to pass by way of the port 80 47 in the valve 50 to the engine cylinder wherein the piston is in such position as to give (so-called) forward motion of the engine crank shaft. And when the engine crank shaft is thereby rotated, the port 55 85 90 permits delivery of air under pressure from the tank 27 to the cylinders 2 and 3 according to the diagram Fig. 4, wherein the arc AB represents approximately the first 120 degrees of downward rotation of the engine 95 crank shaft from the upward dead center, during which portion of the downward stroke of each piston, air is admitted to its cylinder. To effect reverse motion the air is admitted by the opening of throttle valve 100 39 to the air distributing chamber 35 wherein air is distributed by the port 63 according to the diagram Fig. 5, the arc XY representing approximately the first 120 degrees of motion of the crank shaft from 105 upward dead center in the reverse direction, during which period air is periodically admitted to the cylinder. When the engine crank shaft is put in rotation as above described, the throttle valve 37 may be opened, 110 and the oil by-pass valve 72 may be closed or partially closed, whereupon the oil pump 65 will force oil from the oil reservoir 67 through the atomizer 70 into the spray chamber 33 where air under pressure entering from the air tank 27 will cause agitation in the spray chamber 33 still further atomizing the oil sprayed into it and will then carry the oil with it into the gas distributor chamber 42 where it will 115 be distributed by the valve 79 through the port 80 to the engine cylinders 2 and 3 according to the diagram Fig. 6, wherein C representing the point of maximum upward reciprocation or of compression of 120 the charge of air in the cylinder 2 or 3, the arc DE represents the period of injection of the fuel from the gas distributing chamber 42, this being slightly before maximum compression is reached; and 125 130

wherein the arc CF represents the working stroke of the engine piston. During the working stroke the fuel and air charge are burnt, and one of the throttle valves 38 or 39 being open, a supplementary charge of air under pressure is admitted to the engine cylinder during the portion MN of the working stroke. Under such operation of my motor charges of air are periodically taken from the atmosphere to the independent crank chambers where they are compressed. They are then admitted to the engine cylinders when the pistons are individually at their maximum downward position. The air charge is then, during the upward reciprocation of the piston, compressed in the engine cylinder to about ninety pounds or more and just about when maximum compression is reached, fuel is injected and ignited so that when the piston begins its downward stroke the air and fuel is exploded and maximum working pressure is reached in the engine cylinder; the working stroke is then commenced during which for one hundred twenty degrees revolution, air may enter under pressure from the tank 27 so as to maintain the pressure in the working cylinder at about the pressure of the air in the storage tank 27 during more than 120 degrees of the crank shaft rotation. During the remainder of the working stroke the charge works expansively and is exhausted finally through the exhaust port 105. This action of my motor provides its maximum power for excessive load upon the driven shaft 9:

As above described my motor may be started and operated under its maximum power stroke in either direction by opening either the throttle valve 38 or 39 and by causing charges of fuel to be periodically delivered into each engine cylinder. But when so starting the motor, if the driven shaft 9 is under load, the air-clutch-valve 24 must be opened, so that when the engine crank shaft and compressor unit 6 are rotated, the compressor pistons 11 may be revolved about the crank 10 and reciprocated within their cylinders without compressing the air within the compressor cylinders to any greater extent than is required to pass it through the conduits 18 and 19 and the port 23 to the atmosphere. When the air-clutch-valve 24 is opened, the compressor unit 6 may be revolved with respect to the driven shaft 9 with slight resistance, so that the engine crank shaft 4 may attain some speed. When the engine is so operating with the valve 24 opened, there will be little more than atmosphere in the air dome 21, so that under such operation the governor piston 86 and shifting yoke 85 are permitted to remain pressed downward under action of the spring 88 against the eccentric 81, whereby the friction disk 84 engages the friction disk 90. Under such operation therefore, the eccentric 81 is revolved with the shaft 51, so that the auxiliary air pump 92 is actuated, air being thereby compressed into the air tank 27. If now it is desired to put the driven shaft 9 in operation with the engine crank shaft 4, the valve 24 is closed, whereupon the revolving of the compressor unit 6 with respect to the driven shaft 9, causes increased compression of air by the compressor unit into the air dome 21. As the air distributing systems are designed for, a pressure of 300 or 400 pounds, a high pressure will be brought to bear upon the crank 10 of the driven shaft 9, so that it will be revolved with the crank shaft of the engine but at a slower speed. As the compressor cylinders are about the size of the engine cylinders, the high pressure of 300 or 400 pounds in the compressor cylinders will exert large power upon the driven shaft 9. When pressure in the air dome 21 is thereby increased, the governor piston 86 will be raised, whereby the friction disk 84 will be raised from the disk 90 and the air pump 92 will therefore not be operated with the engine. Under such operation when the valve 24 is closed, the air compressed by the compressor unit 6 will pass by the check valve 28 through the conduit 26 into the air tank 27 so that pressure will thereby be maintained in the air tank from which air is distributed through the gas distributing system and one of the air distributing systems into the engine cylinders. When the motor is thus operating with one of the air distributing systems delivering air into each cylinder periodically under high pressure during about 120 degrees of the working stroke, and with fuel being injected into the charge of air compressed in the engine cylinders, the driven shaft 9 will be operated at a considerably slower speed than the compressor unit 6, in order that the compressor unit may supply the large demand of the air and the gas distributing systems, and consequently the driven shaft 9 may be thus operated at maximum load and with maximum torque. When the engine cylinders in this manner operate at maximum power and at considerable speed, the compressor unit 6 may operate at greatest pressure and consequently deliver greatest torque at slow speed of the driven shaft 9. When the load is gotten under way or when the driven shaft may be driven with less torque, the air distributing system may be closed by closing the throttle valve 38 or 39 which has been opened, and then under such operation with the valve 37 open and the valve 72 closed or partially closed fuel and air for spraying will be delivered under pressure through the gas distributing system to each of the engine cylinders periodically and delivered into the charges of air which have

been received from the crank compartments and compressed in the engine cylinders. This is the normal operation and is represented by the diagram Fig. 7, wherein DE 5 is the period of injection of the fuel and CF the working stroke. Under such operation with the air valve 24 closed, as no air can be delivered through the air distributing systems to the engine cylinders from the compressor unit 6, the air pressure in the air dome 21, the compressor unit 6 and the tank 27 will be maintained at high pressure with a comparatively small speed of rotation of the compressor unit 6 with respect to the driven shaft 9 and consequently the driven shaft will be driven with the engine crank shaft at a speed only slightly less than that of the engine crank shaft. The volume of the compressor cylinders should be such that a high pressure of say 300 or 400 pounds will be maintained in the air pressure system with only say about a difference of 50 revolutions in their speeds. Thus there will be only slight slip of the driven shaft under normal operation of the engine. However this proportion of slip may be increased and varied according to the extent to which either of the throttle valves 38 or 39 are opened so that air may be released through the air distributing systems into the engine cylinders.

Although no means is shown for changing the time of injection of the fuel, this being shown to occur at dead center so as to be effective in operation of the engine crank shaft in either direction, it is contemplated that means should be provided for changing the time of injection, especially for a high speed motor, so that the combustion of the fuel may occur most advantageously.

It is to be noted that the principal novel devices of my motor may be used with other detail means for rendering these devices available, such as other forms of valves and other types of engine, as a four cycle engine, and other mechanical devices. It is to be noted also that instead of providing the gas distributing system as shown, the normal air charges taken into each cylinder and compressed therein, may be carbureted before being passed into the engine cylinders, and in such case the compressor unit 6 and the air tank 27 may be used to provide air under pressure only for the air distributing systems for so-called abnormal operation under heavy load and for starting. In such case, under normal operation, no air would be permitted to enter the engine cylinders from the tank 27 and compressor unit 6 and the driven shaft 9 would have only such slip as is necessary to maintain pressure in the compressor cylinders against leakage.

It is to be noted here that instead of having an independent air distributing system the air may be delivered in larger or smaller

quantities through the gas distributing system to effect the purpose of the independent gas distributing systems as shown. It is to be noted also that instead of introducing the fuel to the engine cylinders as shown, any method may be employed for delivering the fuel to the engine cylinders. It is to be noted also that any method may be employed for delivering the extra air from the compressor to the cylinders while still retaining the central principles of my invention. It is to be noted also that instead of having a separate means of supplying the air used for the normal combustion and running of the engine, this air for normal combustion may be supplied by novel means also, the compressor unit in such case supplying all the air to the engine.

It is to be noted here that in practice my motor should preferably be constructed so that under normal operation of the engine, large expansion of the exploded charge is secured, that is a comparatively small charge of air should be drawn into the engine cylinder and compressed to full extent, for normal operation of the engine, so that greater economy may be secured in the normal stroke of the engine, my engine being particularly adapted for such construction as under the abnormal operation described large excess of power may be secured. In conjunction therewith it is to be noted that the fuel pump of my engine should be adapted to supply excess fuel under the abnormal operation described.

What I claim is:

1. In an internal combustion motor, a combustion cylinder, a coöperating piston, means for periodically delivering into the combustion cylinder and compressing therein a primary charge of air, means for burning fuel with the primary charge of air in the combustion cylinder, a driving element, a driven element, a compressor driven by rotation of the driving element relative to the driven element, means for passing air under pressure from the compressor to the combustion cylinder after compression of the primary charge of air in the combustion cylinder.

2. In an internal combustion motor, a combustion cylinder, a coöperating piston, means for periodically delivering into the combustion cylinder and compressing therein a primary charge of air, means for burning fuel with the primary charge of air in the combustion cylinder, a driving element, a driven element, a compressor driven by rotation of the driving element relative to the driven element, means for passing air under pressure from the compressor to the combustion cylinder periodically according to the piston movements therein, and means for controlling the passage of air from the compressor to the combustion cylinder.

3. In an internal combustion motor, engine cylinders, coöperating engine pistons, means for delivering charges of air and fuel periodically to the engine cylinders, a driving element driven by the engine pistons, a driven element, compressor elements respectively operating with the driving element and the driven element, whereby under rotation of the driving element with respect to the driven element, air is compressed, a flexible driving connection between the driving and the driven elements being thereby provided, and means for distributing the air compressed by the compressor elements to the engine cylinders, periodically during the working stroke of the coöperating pistons.
4. In an internal combustion motor, engine cylinders, coöperating engine pistons, means for the combustion of charges of air and fuel periodically in the engine cylinders, a driving element driven by the engine, a driven element, a compressor driven by rotation of the driving element with respect to the driven element, and means for distributing the air compressed by the compressor to the engine cylinders periodically during the working stroke of the related piston.
5. In an internal combustion motor, engine cylinders, coöperating engine pistons, means for delivering charges of air periodically to the engine cylinders, a driving element driven by the engine pistons, a driven element, a compressor driven by rotation of the driving element with respect to the driven element, a flexible driving connection between the driving and the driven element being thereby provided, means for distributing air from the compressor to the engine cylinders, means for mixing fuel with air compressed by the compressor, and means for distributing the fuel to the engine cylinders with the air from the compressor after the mixture of the fuel with air compressed by the compressor.
6. In an internal combustion motor, engine cylinders, coöperating engine pistons, means for delivering charges of air periodically to the engine cylinders, means for injecting fuel periodically to the engine cylinders, a driving element driven by the engine pistons, a driven element, a compressor driven by rotation of the driven element with respect to the driven element, and means for distributing air from the compressor to the engine cylinders and means whereby the resistance of air compressed by the compressor to relative rotation of the driving and driven element, may be varied.
7. In an internal combustion motor, engine cylinders, coöperating engine pistons, means for delivering charges of air periodically to the engine cylinders, a driving element driven by the engine pistons, a driven element, a compressor driven by rotation of the driving element with respect to the driven element, means for injecting fuel periodically to the engine cylinders, a driving element driven by the engine pistons, a driven element, a compressor driven by rotation of the driving element with respect to the driven element, and means for distributing air from the compressor to the engine cylinders under pressure from the compressor to the engine cylinders to support an extended combustion in the engine cylinders during each working stroke, whereby an excess supply of fuel may be burnt in the engine cylinder during each working stroke.

12. In an internal combustion motor, engine cylinders, coöperating engine pistons, means for the combustion of charges of air and fuel periodically in the engine cylinders, 5 a driving element driven by the engine pistons, a driven element, a compressor driven by rotation of the driving element with respect to the driven element, a flexible driving connection between the driving and the driven elements being thereby provided, and a rotary distributor distributing air from the compressor to the engine cylinders periodically and means for controlling the passage of air from the compressor to the 15 engine cylinders.

13. In an internal combustion motor, engine cylinders, coöperating engine pistons, means for the combustion of charges of air and fuel periodically in the engine cylinders, 20 a driving element driven by the engine pistons, a driven element, a compressor driven by rotation of the driving element with respect to the driven element, a rotary distributor adapted to distribute air from the compressor to the engine cylinders for forward movement of the engine, and a rotary distributor adapted to distribute air from the compressor to the engine cylinders for reverse movement of the engine. 25

30 14. In an internal combustion motor, combustion chambers, means for periodically charging the combustion chambers with air, auxiliary means for supplying air under pressure, a rotary distributor distributing air under pressure to the combustion chambers under either forward or reverse movement of the engine, and adapted also to deliver fuel with air under pressure periodically to the combustion chambers.

40 15. In an internal combustion motor, an internal combustion engine, a driving element, driven by the internal combustion engine, a driven element, a main compressor driven by rotation of the driving element with respect to the driven element, a distributor adapted to distribute air from the compressor to the engine cylinders, means for releasing the air compressed by the compressor to the atmosphere, an auxiliary compressor 45 adapted to be operated by the engine, to compress air through the distributor to the engine cylinders, and means whereby the delivery of air under pressure to the distributor from the main compressor will disengage the auxiliary compressor from operation with the engine. 50

55 16. In an internal combustion motor, engine cylinders, coöperating engine pistons, means for delivering charges of air and fuel periodically to each of the engine cylinders, 60 a driving element driven by the engine pistons, a driven element, compressing elements respectively operating with the driving and the driven elements, whereby under 65 rotation of the driving element with respect

to the driven element, air is compressed, and means for distributing the air compressed by the compressor to the engine cylinders, and means for throttling the passage of air from the compressor to the engine cylinders. 70

17. In an internal combustion motor, engine cylinders, coöperating engine pistons, means for delivering charges of air and fuel periodically to each of the engine cylinders, a driving element driven by the engine pistons, a driven element, a compressor driven by rotation of the driving element with respect to the driven element, means for distributing air from the compressor to the engine cylinders, and means for varying the 75 distribution of air from the compressor to the engine cylinders. 80

18. In an internal combustion motor, an engine cylinder, a coöperating engine piston, means for periodically delivering a charge 85 of air and fuel to the engine cylinder, a driving element driven by the engine piston, a driven element, a compressor driven by rotation of the driving element with respect to the driven element, means for passing air from the compressor to the engine cylinder, and means for varying the passage of air from the compressor to the engine cylinder. 90

19. An internal combustion engine, an engine cylinder, a coöperating piston, means for the combustion of charges of air and fuel periodically in the engine cylinder, a driving element driven by the engine, a driven element, a compressor driven by relative rotation of the driving and the driven element, means for passing air compressed by the compressor into the engine cylinder, at will. 95

20. In an internal combustion motor, engine cylinders, coöperating engine pistons, means for the combustion of charges of air and fuel periodically in the engine cylinders, a driving element, a driven element, a compressor driven by rotation of the driving element relative to the driven element, and means for distributing air under pressure from the compressor to the engine cylinders periodically during a portion of each working stroke to sustain pressure in the 100 engine cylinder during a portion of the working stroke. 110

21. In an internal combustion motor, engine cylinders, coöperating engine pistons, means for the combustion of charges of air 120 and fuel periodically in each engine cylinder, a driving element, a driven element, a compressor driven by rotation of the driving element relative to the driven element, means for distributing air from the compressor to the engine cylinders periodically, 125 means for maintaining a supply of air under pressure to pass into the engine cylinders, means for controlling the passage of air from the supply of air under pressure to the 130

engine cylinders, and means for controlling the passage of air from the compressor to the engine cylinders.

22. In an internal combustion engine, engine cylinders, means for periodically supplying each engine cylinder with a charge of air, a driving and a driven element, a compressor operated by rotation of the driving element relative to the driven element, a combining chamber, means for supplying fuel to the combining chamber, means whereby the compressor delivers air into the combining chamber and means for distributing the fluid from the combining chamber to the cylinders of the internal combustion engine after the combination of the air from the compressor with fuel in the combining chamber.

23. In an internal combustion engine, engine cylinders, means for periodically supplying each engine cylinder with a charge of air, a driving and a driven element, a compressor operated by rotation of the driving element relative to the driven element, a combining chamber, means for supplying fuel to the combining chamber, means whereby the compressor delivers air into the

combining chamber, and means for distributing the fluid from the combining chamber to the engine cylinders, after the combination of the air from the compressor with fuel in the combining chamber, and means for controlling the delivery of air from the compressor to the combining chamber.

24. An internal combustion engine, a combustion cylinder, a coöperating piston, means for periodically delivering a primary charge of air into the combustion cylinder, means for delivering fuel into the cylinder, a driving element, a driven element, a compressor driven by rotation of the driving element relative to the driven element, means for passing air under pressure from the compressor to the engine cylinder, after the compression of the primary charge of air in the cylinder.

In witness whereof I have hereunto set my hand this 14th day of September, 1911.

ADOLPHE C. PETERSON.

Witnesses:

JOHN K. LEAK,
C. M. PETERSEN.
